[57] CLAIM

The ornamental design for a quilted bootie, as shown
and described.

DESCRIPTION

FIG. 1 is a side elevational view of a quilted bootie
showing my new design;

FIG. 2 is a rear elevational view thereof;

FIG. 3 is a front elevational view thereof;

FIG. 4 is a top plan view thereof;

FIG. 5 is a bottom plan view thereof;

FIG. 6 is an elevational view of the side opposite that
shown in FIG. 1;

FIG. 7 is a front perspective view of the design shown
in FIGS. 1 through 6 with the drawstring member in a
forward condition and the top sides in a folded condition;

FIG. 8 is a rear perspective view thereof;

FIG. 9 is a side perspective view thereof, the side oppo-
site being substantially a mirror image;

FIG. 10 is a top plan view thereof; and,

FIG. 11 is a bottom perspective view thereof.
